PANEL.

No. 20,360.

Patented Dec. 2, 1890.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,360, dated December 2, 1890.

Application filed November 12, 1889. Serial No. 330,073. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

My design relates to a panel having upon its surface the following ornamental configuration: At the central portion of the panel

is a raised lenticular figure A, upon which appear numerous channels or grooves F, radiating from the center G to the circumference of said figure.
